OIL BURNER

Raymond W. Strawn, Vista, Calif.

Application December 7, 1937, Serial No. 178,523

1 Claim. (Cl. 158—53)

My invention relates to that class of oil burners in which the fuel oils are generated or pre-heated and issue from the fuel nozzle in the form of a gas.

An object of my invention is to produce a fuel oil burner in which the generator is so constructed that it will readily gasify or generate the fuel oil, be efficient in operation, simple in construction and more particularly be so arranged that the generative or pre-heating member may be quickly and easily taken apart and cleaned, when tar, carbon and residue clog it up and prevent efficient operation.

The present invention, together with its objects and advantages, will be best understood from a study of the following description taken in connection with the accompanying drawing, wherein:

Figure 1 is a side elevational view of the complete improved oil burner with fuel oil container and pump attached.

Figure 2 is a longitudinal view of burner taken substantially on the line 2—2 of Figure 3.

Figure 3 is a rear end plan view thereof, illustrating certain details of the dual nozzle jet arrangement and hereinafter more fully referred to. It is taken substantially on line 3—3 of Figure 2.

Figure 4 is a sectional view of pre-heating unit or generator, showing a cross section of the four tubular channels in same, taken at 4—4 of Figure 2.

Referring to the drawing by reference numerals it will be seen that this oil burner comprises a tubular member 11 Figure 2 formed in the general shape of an elongated letter W or capital M fitted with bosses 12, 13, 14 and 15, which support said tubular member 11 concentrically within a shell or drum 16. The front end 17 of said shell is open and rear end 18 of said shell is substantially closed, except for perforations 34—34, which provide for the admission of a part of the air for combustion more fully referred to hereinafter, and tubes 19 and 20 Figure 3, which provide for the admission of generated gas to the burner as it is projected from the jet nozzles 21 and 22.

The terminals 23 and 24 of tubular member 11 Figure 2 extend thru holes in the closed end 18 of cylindrical shell 16 and connected to said terminals, in a gas-tight manner, are fittings 25 and 26.

Fitting 25 is formed in such a manner that two threaded apertures provide separate openings or channels thru the fitting into the upper

tubular arm of member 11. Threaded aperture 28 forms a direct concentric opening into the channel of this tubular arm and provides a means of inserting, when necessary, a cleaning or reaming tool into this portion of member 11, for the removal of carbon and residue from tubular channel 8.

A threaded plug 27 is provided for the closing of this aperture. Aperture 29 forms a lateral passage or channel into upper arm of member 11 and into this aperture is threaded the fuel oil supply pipe line 6. Fitting 26 is also of tubular construction and is formed and threaded onto lower arm of member 11, at terminal 24 in such a manner that when plug 30, and attached screen 31, are removed a direct concentric opening is provided into the lower arm of member 11 for the removal of carbon and residue from tubular channel 2.

Numerals 38 Figure 2 is also a plug screwed into a threaded aperture near the rear central portion of pre-heating member 11, which aperture provides a direct opening or passage into tubular channels 3 and 7 for the removal of carbon and residue therefrom when plug 38 is removed. Therefore, by removing plugs 27, 30 and 38 Figure 2 the entire hollow portion of heating unit member 11, consisting of tubular channels 2, 3, 7 and 8 may be conveniently cleaned of carbon and residue, when necessary, with a suitable ream or cleaning tool.

Plugs 39 and 40 of Figure 2 are for the purpose of closing supporting core projection openings when pre-heating member 11 is made from a metal casting. They are in no way necessary to the efficient cleaning of the device and may be eliminated when said pre-heating unit is fabricated by welding from metal tubing.

Referring to Figure 3 it will be seen that fitting 26 is also provided with two hollow arms 32 and 33, which are placed at right angles to the lower cylindrical portion, are divergent to each other, and constitute an integral part of the fitting. These arms 32 and 33 complete divergent gas-tight channels from the lower arm of the pre-heating member 11 to the twin or dual fuel-jet nozzles 21 and 22 Figures 2 and 3, screwed into said arms.

Numerals 43 of Figure 2 represents one of two screw driven shafts, threaded into the back of arms 32 and 33 at 42, provided with suitable packing glands and each carrying a needle 44 concentric with jet-nozzle orifice 46. It will be seen that by screwing said shafts 43 forward needle 44 is forced thru jet orifice 46, thereby

cleaning and forcing out any flakes of carbon that may accumulate and obstruct said orifice.

Numeral 31 Figure 2 is a cylindrical shaped screen attached to plug 30 and inserted into cylindrical portion of fitting 26 to prevent free carbon and dirt from passing from lower pre-heating unit terminal 24 up thru arms 32 and 33 to close jet orifice 46.

Referring to Figure 3, numeral 34 indicates one of a series of perforations cut in the rear end and near the circumference of the burner shell or drum 16. The index numeral 35 Figures 2 and 3 also indicates one of a series of perforations cut in the circumference and near the rear end of drum 16 for the admission of a controlled amount of air for the combustion of the generated fuel-oil gas, when it has been discharged from the jet nozzles 21 and 22 thru the mixing tubes 19 and 20 into the burner; the complete operation of which is hereinafter described.

Figure 4 is a detail sectional view of the W shaped pre-heating member 11 taken substantially on line 4-4 Figure 2, in which the numerals 8, 7, 3 and 2 indicate the channels in the pre-heating tubular member 11 thru which the incoming fuel oil must pass consecutively in the process of pre-heating or generation.

Numeral 41 Figures 2 and 3 indicates a box-like depression formed in the base of the shell or drum 16 for the purpose of retaining raw or liquid fuel oil while it is being burned in the process of pre-heating the generator member 11 preparatory to the operation of the burner.

From the above description it will be apparent that the burner operates in the following manner:

A quantity of fuel oil is placed in the supply tank, Figure 1. The tank is closed and air pressure is applied to same, by a pump or other pressure supply. A small quantity of the liquid fuel is then placed in generating pan, numeral 41, Figures 2 and 3, and ignited. After burning in this manner for a few minutes, with flame passing around the pre-heating unit 11, said unit becomes hot. Thereupon the operator opens the control valve Figure 1, and allows a certain 45

amount of the fuel oil, now under pressure, to pass into and thru supply pipe 6, thence thru fitting 25, where it enters the upper and now heated channel 8 of pre-heating unit 11 Figure 2. The liquid fuel coming in contact with heated walls of channel 8 begins to gasify and as it progresses it reverses direction upon entering each of the consecutive channels 7, 3 and 2, moving first towards the front and then towards the rear of burner, until finally in a highly heated, agitated and gasified state it passes from pre-heating unit 11 thru screen 31 thence thru fitting arms 32 and 33 to be discharged from nozzles 21 and 22 Figures 2 and 3, thru mixing tubes 19 and 20, into the combustion chamber of the burner. Here it becomes mixed with additional air from the series of perforations 34 and 35. This highly combustible gas is now ignited by the operator or by flame that may remain in the generating pan 41, and issues with considerable velocity and intense heat from the front end of burner drum at 17, where it is used for burning weeds, killing pests, disinfecting and various other purposes, or as an industrial heating unit.

While the particular form of oil burner herein described is well adapted to carry out the objects of the invention, the invention is capable of all such modifications and changes as come within the scope of the appended claim.

I claim:

1. In an oil burner of the character described, a cylindrical shell defining a burning chamber, an oil vaporizing member disposed within said burning chamber, means for attaching said oil vaporizing member to said burning chamber to be supported thereby, said oil vaporizing member consisting of a plurality of substantially straight tubular portions connected to form a W-shaped passage, a plurality of jets connected to one end of said oil vaporizing member and positioned to direct the vapor therefrom into said burning chamber longitudinally and in a direction to encounter the W-shaped oil vaporizing member, and detachable closure members on each of said straight portions of said gas vaporizing member.

RAYMOND W. STRAWN.
